US0D1023043S

(12) **United States Design Patent** (10) **Patent No.:** **US D1,023,043 S**
(45) **Date of Patent:** **** Apr. 16, 2024**

(54) **DISPLAY SCREEN OR PORTION THEREOF
WITH A GRAPHICAL USER INTERFACE**

(71) Applicant: **PassiveLogic, Inc.**, Salt Lake City, UT
(US)

(72) Inventor: **Troy Aaron Harvey**, Brighton, UT
(US)

(73) Assignee: **PassiveLogic, Inc.**, Salt Lake City, UT
(US)

(**) Term: **15 Years**

(21) Appl. No.: **29/817,670**

(22) Filed: **Dec. 2, 2021**

(51) **LOC (14) Cl.** **14-04**

(52) **U.S. Cl.**

USPC **D14/486**

(57) **CLAIM**

The ornamental design for a display screen or portion thereof with a graphical user interface, as shown and described.

DESCRIPTION

The FIGURE is a front view of a display screen or a portion thereof with a graphical user interface.

The outermost broken lines illustrate a display screen or portion thereof and form no part of the claimed design.

1 Claim, 1 Drawing Sheet
